UNITED STATES PATENT OFFICE

166,150

APRON OR SIMILAR ARTICLE

Diana Forest, New York, N. Y.

Application August 15, 1951, Serial No. 16,289

Term of patent 3½ years

(Cl. D3—26)

To all whom it may concern:

Be it known that I, Diana Forest, a citizen of the United States of America, residing in New York, county of New York, and State of New York, have invented a new, original, and ornamental Design for an Apron or Similar Article, of which the following is a specification, reference being had to the accompanying drawing, forming part thereof,

Fig. 1 is a plan view of an apron or similar article, showing my new design.

Fig. 2 is a side elevational view thereof.

I claim:

The ornamental design for an apron or similar article, substantially as shown.

DIANA FOREST.
